UNITED STATES PATENT OFFICE

JAMES HERBERT WAINWRIGHT GILL, OF LONDON, ENGLAND

ROTOR FOR AXIAL FLOW HYDRAULIC MACHINES

Application filed December 31, 1930, Serial No. 505,890, and in Great Britain February 4, 1930.

This invention relates to screw rotors for hydraulic machines wherein the general direction of flow through the rotor is axial or more nearly axial than radial, and has further reference to the combination of such rotors with suitable casings and with guide vanes or their equivalent, to constitute such hydraulic machines.

The design of such rotors has hitherto been based on the broad assumption that substantially the same speed of inflow normally obtains along all the concentric stream tubes passing through a cross section in the annulus between the periphery and the boss of the rotor. Frictional retardation at the outer and inner boundaries of the annulus results, however, in axial flow speeds which decrease progressively with proximity to these boundaries, and this effect increases with the length of the intake passage and of the bossing or core, also with the viscosity of the fluid, and with the proportion of solid matter in suspension therein.

It is known to be desirable in many axial flow machines to provide for a substantially uniform distribution of head over the rotor face, and rotors have been designed to this end on the assumption of a correspondingly uniform axial flow, without consideration of the frictional retardation referred to herein, or of centrifugal effect due to the steep rise of root pitches.

The primary object of the present invention is to provide a rotor construction with which the practical performance shall be equivalent to the performance which is calculated from the theoretical assumption of uniform axial flow with uniform head, notwithstanding the modifying effect of surface retardation on flow volume, and of centrifugal tendency at the blade root pitches. This object is accomplished by departing from the incidence of rotor blade pitch which is calculated from the accepted theoretical assumptions as to uniform axial flow speed and head distribution, and replacing this by an incidence of blade pitch which is relatively steeper towards the mid-annulus sections of the rotor blades.

A further object of the invention is so to

construct the rotor that when applied to an axial flow pump all unnecessary shock at inlet to the rotor is eliminated, more especially in the neighbourhood of the boss where the pitch is steeper, and progressive impartation of energy to the fluid in its passage through the rotor is ensured, whilst in the case of an axial flow reaction turbine the converse effect of progressive reception of energy is attained.

In the rotor according to this invention the pitch of the blades gradually increases radially inwards from a chosen value at the periphery of the rotor at such a rate that the pitch at any radius r is equal to or less than

$$\frac{KR}{r}$$

and is greater than

$$\frac{KR^a}{r^a}$$

where R is the peripheral radius, K is the chosen peripheral pitch value and a is the ratio of the boss radius to the peripheral radius. For fluids of relatively high viscosity or fluids having a relatively large amount of solid matter in suspension, the pitch profile curve (i. e. the curve of pitch plotted against radius) is arranged to approach nearer to the upper limit curve

$$P = \frac{KR}{r}$$

(where P is the pitch at radius r) than for fluids of relatively low viscosity. Even with fluids of low viscosity, however, it is seldom desirable to approach close to the lower limit curve

$$P = \frac{KR^a}{r^a}$$

at the inner radii in any case, and it will generally be preferable for the pitch to be greater than

$$K \left(\frac{R}{r} \right)^{a+0.1}$$

The definition of limits above expressed

necessarily includes a variety of pitch profile curves (e. g. curves having sudden discontinuities or abrupt changes of slope or repeated undulations) which result in impracticable rotor designs, but it is to be understood that the invention only contemplates generally smooth curves (within the limits) such as will conform with the natural conditions of flow and will produce, when the rotor is operating on water under normal designed conditions, a value of pitch at the periphery of the blades which when multiplied by the number of revolutions per unit time gives a figure less than one and a half and usually less than one and a quarter times the mean axial speed of flow (i. e. to accommodate values of slip ratio at the periphery less than 33 1/3% and usually less than 20%). In most cases where the boss diameter is moderate the pitch at the blade tips is chosen to suit operation (with water as the working fluid) at a peripheral slip ratio between 10% and 15%, calculated on the mean desired speed of flow.

The size of boss selected will vary to some extent in accordance with the type of machine in which the rotor is to be used as well as on the conditions of operation. For an axial flow pump or reaction turbine the boss radius may be from three-eighths to three-quarters of the peripheral radius according to the area necessary to accommodate the normal desired flow with a given head and speed, whilst for reaction propellers the lower boss radius limit may be extended to a fifth 35 of the peripheral radius.

In a preferred typical construction of rotor for use in an axial flow pump designed for operation on water, the pitch increases from the periphery to a mid-radius blade section 40 approximately in accordance with the law

$$P = K \left(\frac{R}{r} \right)^{0.75}$$

and thence increases smoothly but more rapidly to a value approximate to

$$\frac{KR}{r}$$

at the boss, the boss having a radius between 50 three-eighths and one-half of the peripheral radius.

According to a further important feature of the invention, the rotor blades are given an axial variation in pitch in addition to the 55 radial variation in pitch. In this case the pitch in the neighbourhood of one edge of the blades (namely the discharge edge for a pump rotor or the intake edge for a turbine rotor) will lie within the limits above mentioned, 60 whilst the pitch in the neighbourhood of the other edge will be lower and may have an approximately constant value corresponding to the chosen peripheral pitch value, the axial transition of pitch along concentric stream 65 tubes following smooth curves. In hydraulic

screw turbines and in axial flow pumps operating at slip ratios above normal values, or on viscous fluids, this axial variation of pitch is of great importance, as it provides for maximum deflection of the fluid flow within the 70 rotor in the case of turbines, and for smooth intake to the steeper sections of the rotor in the case of pumps.

The invention may be carried into practice 75 in various ways depending on the type of hydraulic machine in which the rotor is used, also on the nature of the working fluid and on the conditions of operation, but a preferred construction of rotor according to the invention and some convenient applications thereof 80 to hydraulic machines are illustrated by way of example in the accompanying drawings, in which

Figure 1 is a graph illustrating the pitch 85 distribution in the blades of a rotor according to the invention,

Figure 2 shows a central section through 90 an axial flow pump designed more especially for operation on water and employing the preferred form of rotor,

Figure 3 shows a projection of half the 95 rotor of Figure 2 on a transaxial plane,

Figure 4 is a similar half transaxial projection of the outlet guide vanes employed in the pump of Figure 2,

Figure 5 illustrates one convenient application of the preferred form of rotor to an axial flow reaction turbine,

Figures 6-8 are views similar to those of 100 Figures 2-4 for a modified form of axial flow pump,

Figures 9 and 10 are views similar to those of Figures 2 and 4 for another modified form of axial flow pump, and

Figures 11 and 12 respectively illustrate 105 two further modifications.

The graph of Figure 1 shows a series of pitch profile curves (i. e. curves showing the relative pitch in the rotor blades plotted against distance from the axis of the rotor) for various rotors according to the invention. For purposes of comparison, the pitch profile curve for a typical uniform head rotor designed in the usual manner on the assumption of uniform axial flow is shown at A¹ 110 in chain line, whilst the dotted line A² is the corresponding curve for a uniform pitch rotor. The curves A³, A⁴, A⁵, A⁶ relate to rotors according to the invention, the curve A³ representing the preferred form, whilst the curves A⁴, A⁵ are respectively the upper 115 and lower limit curves, and the curve A⁶ is another limiting curve.

The preferred form of rotor, two views of 125 a typical construction of which are shown in Figures 2 and 3, has from two to six blades B (five being shown in Figures 2 and 3) carried by a cylindrical boss C, which is mounted within a cylindrical casing D on the driving shaft C¹. In the example illustrated, the 130

boss C has a radius of two-fifths of the peripheral radius of the rotor blades. The edges of the blades at one end of the rotor lie on the surface of a coaxial cone, whilst those at the other end lie in a transaxial plane or on the surface of another coaxial cone of different or of opposite vertical angle, so that the axial length of the rotor is considerably greater at the boss than at the periphery, the straight-line A⁷ in Figure 1 showing the profile view of one edge of the blades for the case when the horizontal base line A⁸ of the graph represents the profile view of the other edge of the blades. The rotor shown in Figure 2 has its discharge edge B¹ conforming to the line A⁷ of Figure 1, its inlet edge B² lying on a transaxial plane, whilst the rotor employed in the turbine of Figure 5 has its edges on the surfaces of coaxial cones of opposite vertical angle.

In face projection on a transaxial plane (see Figure 3) the edges B¹, B² of the blades do not overlap and are convex with reference to straight lines joining the roots and tips of the blades, the degree of convexity and distribution of blade area being governed by the incidence of blade pitch at the different radii taken in conjunction with the degree of substantially straight line taper in the profile view of the blades. The total face projected area of the blades lies between, say, 60% and 80% of the total projected area of the annulus between the boss and the periphery, depending upon the loading allowed for per unit of blade area and the amount of guidance required by the fluid.

The pitch distribution in the blades of the rotor can best be described with reference to the graph of Figure 1. In this graph the abscissæ are radial distances from the axis of the rotor, the graph extending from the surface of the boss to the periphery of the rotor whilst the peripheral radius is taken as the unit. The ordinates represent the pitch at the various radii, the peripheral pitch value being taken as the unit. As above mentioned the curve A⁴ represents the upper limit pitch profile curve and follows the law

$$P = \frac{KR}{r}$$

whilst the curve A⁵ represents the lower limit curve defined by the law

$$P = K \left(\frac{R}{r} \right)^a$$

where $a=0.4$ in the example chosen. Whilst the invention comprises within its scope all rotors whose radial distribution of pitch conforms to a generally smooth curve lying between these two limiting curves, it is seldom desirable to approach close to the lower limit curve A⁵, and in the majority of instances

the pitch profile curve will lie above the curve A⁶, which conforms to the law

$$P = K \left(\frac{R}{r} \right)^{a+0.1}$$

i. e. in the example illustrated

$$P = K \sqrt{\frac{R}{r}}$$

The preferred rotor conforms to the curve A³. This curve extends from the peripheral pitch value, which is chosen to suit operation at a normal peripheral slip ratio of, say, 12.5% calculated on the mean axial flow speed, and increases from this value to a mid-blade radius (at seven-tenths of the peripheral radius) in accordance approximately with the law

$$P = K \left(\frac{R}{r} \right)^{0.75}$$

so that the mid-radius pitch value is about 1.3 times the peripheral pitch value. From the mid-radius inwards to the boss the rate of increase of pitch is greater than that given by this law, and at the boss the pitch reaches a value 2.5 times the peripheral pitch, the pitch profile following a smooth curve from boss to periphery. This pitch distribution profile curve A³ (as also all other pitch profile curves within the scope of the invention) is less hollow than the curve A¹ for the known uniform head rotors designed on the assumption of uniform axial flow, and by accelerating the flow through the middle portion of the annulus it enables the desired compensation to be obtained for the effect of surface retardation, and allows for the different centrifugal tendencies at the different radii. In the case of working fluids of higher viscosity than that of water, a pitch profile curve flatter than the curve A³ may be used, the ratio of mid-blade pitch to peripheral pitch being increased by an amount dependent on the viscosity of the fluid, whilst the ratio of the pitch at the boss to the peripheral pitch remains at 2.5 for the same boss diameter ratio.

In addition to the radial variation of pitch above described, the rotor blades may also have an axial pitch variation. In one convenient arrangement (incorporated in the rotor of Figures 2 and 3) the blades have the same peripheral pitch value at the discharge edge B¹ and at the inlet edge B², and the pitch along the discharge edge B¹ conforms to the curve A³, whilst along the inlet edge B² the pitch is uniform at all radii (conforming to the straight line A²) or increases only slightly inwards, the pitch varying continuously and smoothly along each stream tube from its inlet edge value to its discharge edge value.

The manner in which the rotor is employed in an axial flow hydraulic machine will de-

- pend on the type of machine and on the conditions in which the machine is to operate. In the case of an axial flow pump it will usually be preferable to mount the rotor within a cylindrical casing between coaxially-arranged inlet and outlet guide vanes, although in certain instances, for example when the direction of discharge is to be at right angles to the axis of the rotor within a confined space, the coaxial outlet guide vanes may be situated in expanded sections of the casing, whilst in extreme cases these guide vanes may be replaced by a whirl chamber of expanding trumpet shape with a central core or of a scroll or volute form, or by adjustable guide vanes of the balanced wicket type, the last mentioned alternatives also being especially suitable for the reverse application to an axial flow reaction turbine. In other instances for other hydraulic machines as well as for pumps, for example when the head is high and the revolution speed moderate, a second oppositely-rotating coaxial rotor may replace the outlet guide vanes. Typical instances of such hydraulic machines are illustrated in Figures 2-12 of the accompanying drawings.

Thus in the axial flow pump shown in Figures 2-4, the rotor as above described operates between adjacent fixed coaxial guide vanes in a cylindrical casing D. The inlet guide vanes E are preferably from two to six in number and may be arranged radially or tangentially or may be curved in plan view. These vanes are normally designed to maintain an axial direction of inflow to the rotor, although they may be curved towards or against the direction of rotation of the rotor to accommodate or to impose special conditions of inflow.

The outlet guide vanes F are preferably from four to eight in number (six as shown) and have their inlet edges F¹ so curved as to receive the fluid approximately in its absolute direction of discharge from the rotor, making a small angle with a transaxial plane near the boss and a larger angle therewith near the periphery. The function of these vanes is to recover head or pressure energy from the whirl imparted to the fluid by the rotor. The degree of curvature of these vanes is governed by the law $s \tan \gamma = (1-s) \tan \beta$, where β and γ represent the angles made with a surface normal to the stream tube at any radius, by the outlet edge of the rotor blade and by the inlet edge of the outlet guide vane respectively, whilst s is the slip ratio at that radius. The discharge edges F² of the outlet guide vanes are designed to promote an approximately axial direction of outflow and the vanes themselves may be arranged tangentially (as shown) or radially or curved in plan view. The cross-sections of these vanes are preferably of such stream-lined form and thickness that the sector-shaped spaces between the

vanes follow, in the direction of flow, approximately the changes of cross-sectional area proper to expanding passages for the maximum recovery of head.

The spacing between the rotor and the adjacent edges of the guide vanes will normally be made small, but for the purpose of dealing with solid matter in suspension or for meeting considerable variations in pumping duty, this spacing may be varied, a radially outwards increase in this spacing being desirable in many cases even when solid matter is not present.

The shape and size of the bosses E¹ F¹ situated in the spaces occupied axially by the guide vanes are arranged to suit those of the rotor boss C, and in some instances it may be desirable to depart from a cylindrical shape for the rotor boss, in which case the body representing the combined rotor and guide vane bosses E¹, C, F¹ as a whole may be of streamlined or tapered or bulbous or other suitable shape. The casing D will have such shape in relation to that of the bosses as may be necessary to regulate the area for axial flow.

The arrangement above described, as also the modified forms of axial flow pump to be described later, is operable in reverse as an axial flow reaction turbine. It will however usually be preferable to employ a volute chamber or balanced wicket guide vanes for controlling the turbine inflow, and one such convenient application of the invention to an axial flow turbine is illustrated in Figure 5. In this arrangement the rotor G, which is constructed in the manner above described, rotates within a vertical casing H of generally cylindrical shape. The inflow to the top of the casing H takes place through an inclined annular passage H¹ and is controlled by guide vanes J of the balanced wicket type, these vanes being simultaneously adjustable by suitable means such for instance as the rotatable slotted crown J¹. In this construction the rotor G is adjustable in an axial direction (as indicated by the dotted lines) in order to accommodate varying conditions of operation.

In some instances, both for pumps and for turbines, it may be convenient so to design the rotor that it may readily be interchanged with other rotors according to the invention, such rotors having approximately the same axial length but having different nominal pitch values and correspondingly different numbers of blades. Again, it is sometimes necessary to provide for inspection and cleaning of the working parts of a pump, without dismantling the casing, and in order that this may be readily effected, the outlet and inlet guide vanes between which the rotor operates may be fixed to a removable liner within the casing instead of to the casing itself, whereby the whole pump can be lifted bodily out of the casing, and the inlet guide vanes may be

so arranged that the rotor can be passed axially between these vanes, if desired.

In other instances changes in the normal working conditions can be accommodated by 5 rotation of the rotor blades about their radial axes. A convenient practical arrangement of this kind is illustrated in Figures 6-8. In this arrangement each of the rotor blades K is made with a trunnion extension K¹ which 10 is tightly gripped in the boss, which is transversely cut into two halves L, L¹ for the purpose, the two halves of the boss being held together by means of bolts L² engaging in grooves K² in the trunnions in order to hold 15 the blades radially in position against centrifugal action.

Whilst it is true that such rotational adjustment of the rotor blades will throw them somewhat out of pitch, and thereby slightly 20 lower the efficiency of the pump, the law governing the pitch distribution in the rotor according to the invention is such that the loss in efficiency by rotation of the blades through, say, 7° on either side of the normal 25 position will be very small, and the disadvantage of such a reduction in efficiency is amply made up for by the advantage of the adaptability of the pump to varying working conditions. An alternative method of 30 mounting the blades is to provide a slotted flange on the root of the blade, by which it can be bolted on to the boss, the slots in the flange being of such a length as to allow the desired 7° adjustment on either side of the 35 normal blade position.

The inlet guide vanes M are fixed between a boss M¹ and the cylindrical casing M² and are arranged in a manner generally similar to that of the inlet guide vanes in the construction of Figures 2-4. Whilst the outlet guide vanes may also be fixed as in the construction of Figures 2-4, Figures 6-8 serve to show a modified arrangement of these 40 vanes wherein they are rotatable about their longitudinal axes to accommodate changes in the absolute direction of discharge from the rotor incident upon changes in the normal working conditions and also to suit rotational adjustment of the rotor blades. To 45 this end each of the outlet guide vanes N is supported on a short shaft N¹ extending through the wall of the casing M² and is gripped in position by means of a nut N² on the end of the shaft N¹. In other respects 50 the outlet guide vanes N are arranged generally in the same manner as the outlet guide vanes in the construction of Figures 2-4.

Instead of mounting the outlet guide vanes 55 rotatably in the casing, a generally similar result can be obtained by providing these vanes with adjustable inlet edges. Such an arrangement is shown in Figures 9 and 10, wherein each outlet guide vane is formed in two parts O, O¹, the upper part O being 60 fixed in the casing whilst the lower part O¹

is provided with a circular flange O² fitting into a hole in the casing. This arrangement not only allows slight rotational adjustment of the inlet part O¹ of the vane, but also permits ready removal of this part of the vane 70 and substitution of a differently curved alternative inlet edge for the vane.

Figure 9 also serves to show a modified arrangement for the inlet guide vanes (equally applicable to the constructions of axial flow 75 pump shown in the other figures), especially intended for instances in which the pump is operating on liquids with solid matter in suspension. In this arrangement each inlet vane is made up of a series of tongues P bolted to narrow plates P¹ extending radially inward from the casing and joined together at the axis, the upper edges of the tongues lying adjacent to the inlet edges of the rotor blades. In the example illustrated four such tongued 80 inlet vanes are employed, and the arrangement is such that, in addition to performing their normal function of guiding the liquid properly to the rotor, these guide vanes cooperate with the rotor Q to effect disintegration of any solid matter present in the liquid.

Figure 11 illustrates a further modification of axial flow pump in which outlet guide vanes are dispensed with altogether. In this 95 instance the casing R is provided with a trumpet-shaped extension R¹ on the discharge side of the rotor S, and a central core R² is provided which is so shaped as to conform to the rotor boss S¹ and to form with 100 the casing extension R¹ a discharge whirl chamber having a varying cross-sectional area such as to give regular recovery of whirl and of flow velocity head from the rotor to the discharge orifice. With this arrangement it is sometimes desirable to have adjustable inlet guide vanes to accommodate 105 changes in the normal working conditions, and to this end the inlet guide vanes T are each supported on a short shaft T¹ extending through the wall of the casing R, the arrangement being generally analogous to the rotatable outlet guide vane arrangement 110 of Figures 6-8.

Figure 12 shows an arrangement in which 115 the outlet guide vanes are replaced by a second rotor, and whilst this arrangement will be described with reference to its use as an axial flow pump, it will be appreciated that it can readily be employed as a power transmitter or for other purposes. In this arrangement the two rotors U, V are mounted on coaxial shafts U¹, V¹ extending through the walls of the casing W, which is suitably curved for the purpose, as shown, the central part of the casing adjacent to the rotors being approximately cylindrical. The two shafts U¹, V¹ rotate in opposite directions as indicated by the arrows and the two rotors 120 are correspondingly "right-handed" and 130

"left-handed". The rotor U at the inlet side is constructed in the manner above described, but the second rotor V (whose function in a pump is similar to that of outlet guide vanes) 5 has a pitch distribution in its blades suited to the proper conversion of the discharge whirl from the rotor U into pressure head. The inlet guide vanes in this instance are replaced by a stream-lined fin W¹ supporting 10 the shaft U¹, and a similar supporting fin W² may be provided for the shaft V¹.

Axial-flow pumps having rotors according to this invention may also be constructed as multi-stage series pumps, with two or 15 more rotors on the same shaft, separated by fixed guide vanes, which (when the series stages are close together) may be designed to serve as outlet guide vanes for one rotor and as inlet guide vanes for the next rotor 20 in the series.

The rotor may also be used either alone or in combination with guide vanes or additional rotors in other axial flow hydraulic machines such for example as propellers, 25 mixers or power converters.

It will be appreciated that the particular arrangements above referred to may be modified to suit requirements within the scope of the invention; for example, the profile and 30 face projections of the rotor blades may follow various forms and area ratios and the rotors may be of open or of shrouded type, whilst cylindrical sections of the rotor blades may follow stream-lined or other suitable 35 form.

What I claim as my invention and desire to secure by Letters Patent is:—

1. A rotor for an axial flow hydraulic machine comprising a boss, and blades carried 40 thereby, the pitch of the blades gradually increasing radially inwards from a chosen value at the periphery of the rotor at such a rate that the pitch at radius r is considerably less than

$$45 \quad \frac{KR}{r}$$

but is greater than

$$50 \quad \frac{KR^a}{r^a}$$

except in the neighborhood of the boss where the pitch increases rapidly towards a value approximating to

$$55 \quad \frac{KR}{r},$$

where R is the peripheral radius, K is the chosen peripheral pitch value and a is the 60 ratio of the radius of the boss to the peripheral radius.

2. A rotor for an axial flow hydraulic machine, comprising a boss, and blades carried thereby, the pitch of the blades gradually increasing radially inwards from a chosen val-

ue at the periphery of the rotor at such a rate that the pitch at radius r is considerably less than

$$70 \quad \frac{KR}{r}$$

but is greater than

$$75 \quad K \left(\frac{R}{r} \right)^{a+0.1}$$

except in the neighborhood of the boss where the pitch increases rapidly towards a value approximating to

$$80 \quad \frac{KR}{r}$$

where R is the peripheral radius, K is the chosen peripheral pitch value and a is the ratio of the radius of the boss to the peripheral radius.

3. A rotor for an axial flow hydraulic machine, comprising a boss, and blades carried thereby, the pitch of the blades gradually increasing radially inwards from a chosen value at the periphery of the rotor at such a 90 rate that in the outer half of the rotor the pitch at radius r has a value approximating to

$$95 \quad K \left(\frac{R}{r} \right)^{0.76}$$

where R is the peripheral radius, K is the chosen peripheral pitch value and a is the ratio of the radius of the boss to the peripheral radius, whilst in the inner half of the 100 rotor the pitch increases more rapidly so that at the boss it has a value approximating to

$$105 \quad \frac{K}{a}$$

4. A rotor for an axial flow hydraulic machine comprising a boss, and blades carried thereby, the pitch of the blades at one edge of the rotor gradually increasing radially inwards from a chosen value at the periphery of the rotor at an increasing rate such that the pitch at radius r is equal to or less than

$$115 \quad \frac{KR}{r}$$

and greater than

$$120 \quad \frac{KR^a}{r^a},$$

where R is the peripheral radius, K is the chosen peripheral pitch value and a is the ratio of the radius of the boss to the peripheral radius, the pitch and the rate of radial increase of pitch both decreasing gradually 125 in an axial direction towards the other edge of the rotor.

5. A rotor for an axial flow hydraulic machine, comprising a boss, and blades carried thereby, the pitch of the blades gradually 130

increasing both radially inwards from the periphery of the rotor to the boss and axially from one edge of the rotor to the other in such a manner that in the neighbourhood of one edge of the rotor the pitch increases radially inwards from a chosen value K at the periphery at an increasing rate such that at any radius r the pitch lies between

$$\frac{KR}{r}$$

and

$$\frac{KR^a}{r^a}$$

(where a is the ratio of the radius of the boss to the peripheral radius), whilst in the neighbourhood of the other edge of the rotor the pitch has a value approximating to K at all radii.

6. A rotor for an axial flow hydraulic machine, comprising a boss, and blades carried thereby, the pitch of the blades at the periphery of the rotor being chosen to suit operation (with water as the working fluid) at a peripheral slip ratio of between 10% and 25%, the pitch of the blades gradually increasing radially inwards from this peripheral value at such a rate that the pitch at radius r is considerably less than

$$\frac{KR}{r}$$

but is greater than

$$\frac{KR^a}{r^a}$$

except in the neighborhood of the boss where the pitch increases rapidly towards a value approximating to

$$\frac{KR}{r}$$

where R is the peripheral radius and K is the chosen peripheral pitch value, whilst a which lies between one-fifth and three-quarters is the ratio of the radius of the boss to the peripheral radius.

7. A rotor for an axial flow hydraulic machine comprising a boss, and blades so mounted on the boss that each blade can be rotatably adjusted about a radial axis through a small angle on either side of a normal position, the pitch of the blades when in their normal position gradually increasing radially inwards from a chosen value at the periphery of the rotor at an increasing rate such that the pitch at radius r is equal to or less than

$$\frac{KR}{r}$$

and greater than

$$\frac{KR^a}{r^a}$$

where R is the peripheral radius, K is the

chosen peripheral pitch value and a is the ratio of the radius of the boss to the peripheral radius.

8. The combination with the features set forth in claim 1, of a casing surrounding the rotor, guide vanes mounted coaxially with and adjacent to the rotor on both sides thereof within the casing, and means whereby each of the guide vanes on one side of the rotor can be rotatably adjusted about its longitudinal axis. 70 75

9. The combination with the features set forth in claim 7, of a casing surrounding the rotor, guide vanes mounted coaxially with and adjacent to the rotor on both sides thereof within the casing, and means whereby each of the guide vanes on one side of the rotor can be rotatably adjusted about its longitudinal axis. 80

10. The combination with the features set forth in claim 1, of a casing surrounding the rotor, and guide vanes mounted coaxially with and adjacent to the rotor on both sides thereof within the casing, each of the guide vanes on one side of the rotor being divided longitudinally into two parts, of which the part nearer to the rotor is so mounted as to be readily removable and replaceable by a similar but differently curved part. 85

11. The combination with the features set forth in claim 1, of a casing surrounding the rotor, a suitably shaped whirl chamber constituting an extension of the casing on one side of the rotor, and guide vanes mounted coaxially with and adjacent to the rotor within the casing on the other side thereof, each of such guide vanes being rotatable about its longitudinal axis. 90 95

12. The combination with the features set forth in claim 4, of a casing surrounding the rotor, a suitably shaped whirl chamber constituting an extension of the casing on one side of the rotor, and guide vanes mounted coaxially with and adjacent to the rotor within the casing on the other side thereof, each of such guide vanes being rotatable about its longitudinal axis. 105 110

In testimony whereof I have signed my name to this specification.
